UNITED STATES PATENT OFFICE.

JEROME R. GEORGE, OF WORCESTER, MASSACHUSETTS, ASSIGNOR TO THE MORGAN CONSTRUCTION COMPANY, OF WORCESTER, MASSACHUSETTS, A CORPORATION OF MASSACHUSETTS.

CARRIER FOR THE TOP ROLLS OF ROLLING-MILLS.

SPECIFICATION forming part of Letters Patent No. 729,569, dated June 2, 1903.

Application filed June 11, 1900. Serial No. 19,949. (No model.)

To all whom it may concern:

Be it known that I, JEROME R. GEORGE, a citizen of the United States, and a resident of Worcester, in the county of Worcester and 5 Commonwealth of Massachusetts, have invented certain new and useful Improvements in Carriers for the Top Rolls of Rolling-Mills, of which the following is a specification, reference being had to the accompanying drawings, forming a part of the same, in which—

Figure 1 represents a top view of a rolling-mill housing with the upper roll removed and the housing shown in sectional view on line 11, Fig. 2. Fig. 2 is an end view with a portion of the housing broken away for the purpose of showing the screw for tightening the roll-carrier. Fig. 3 is a perspective view of the actuating-wedge by which the roll-carrier is pressed against the gudgeon of the roll.

20 Similar reference-letters refer to similar parts in the different views.

My invention relates to a carrier or support for the gudgeon of the upper roll of a rolling-mill by which the weight of the upper roll is supported and the roll held in proper operative position relatively to the lower roll; and it consists in providing a bearing-surface beneath the gudgeon of the upper roll by the employment of a pair of blocks inserted between the gudgeons of the upper and lower rolls and crowded apart, so as to press the lower block of the pair against the gudgeon of the lower roll and the upper block of the pair against the gudgeon of the upper roll.

35 Referring to the drawings, A A represent the housings of a rolling-mill containing a lower roll B and an upper roll C, having gudgeons B' and C' at opposite ends of the rolls, the gudgeons B' of the lower roll resting in bearings B² in the housings. Between each pair of gudgeons B' and C', I place two blocks D and E, preferably of wood. The block D is beveled at one end and on its upper side 40 at D', and the block E is similarly beveled at one end and on its under side at E', forming a triangular opening at one end of the blocks to receive a wedge F, provided at its center with a screw-threaded opening F' to receive 45 the screw-threaded end of a bolt G, which is

supported in the housing and is provided with a collar G', held in a recess G² in the housing, by which the bolt G is held from longitudinal movement. The end G³ of the bolt is squared to receive a wrench, by which the 55 bolt may be rotated and the wedge F forced between the beveled ends of the blocks D and E by the action of the screw-thread. The blocks D and E when placed between the gudgeons B' and C' nearly or quite fill the 60 space between the gudgeons, so that a slight movement of the wedge F in forcing the blocks D and E apart at one end will crowd the blocks together at their opposite ends and carry their central sections against the gudgeons of the upper and lower rolls. The 65 blocks serve as levers, with their contacting ends held from movement and acting as fulcrum, which are located entirely at one side of the vertical plane containing the axes of the 70 rolls, and the pressure of the wedge against the beveled ends of the blocks on the opposite side of said vertical plane will press the upper block against the gudgeon C' of the upper roll and the lower block against the gudgeon B' of the lower roll, thereby spreading the blocks apart and supporting the weight 75 of the upper roll.

It has been customary heretofore to employ a metal cap-block resting upon the gudgeon 80 of the lower roll and a carrier-block supporting the gudgeon of the upper roll, said carrier-block fitting the gudgeon and being capable of a direct vertical movement by means of a wedge located directly beneath the axis 85 of the upper roll and acting against opposite-inclined surfaces on the cap-block and carrier-block; but I do not claim such a construction.

My improved top-roll carrier consists, preferably, of a wooden block having parallel sides adapted to bear against the gudgeon of the upper roll and having a short beveled surface at one end to receive the contact of the wedge, while the opposite end is held from movement, thereby serving as a fulcrum on which the block is rocked by the action of the wedge. As the beveled ends of the blocks are free to move, the wedge is capable of being held upon the screw-threaded end of the 90 95 100

bolt or shaft journaled in the roll-housings, whereas by the usual construction of wedge-actuated top-roll carriers provision must be made for the vertical movement of the wedge 5 as it slides upon the inclined upper surface of the lower or cap block. The actuating-wedge F is a short wedge entering but a short distance between the ends of the blocks D and E. The opposite or contacting ends of 10 the blocks D and E are free to move up and down within the housing, so that the rolls may be adjusted vertically in the housing without requiring a readjustment of the actuating-wedge, the rising or falling motion of 15 the rolls imparting a slight rising or falling motion to the contacting ends of the blocks D and E.

What I claim as my invention, and desire to secure by Letters Patent, is—

20 1. The combination with a rolling-mill housing and a pair of rolls held therein, of means for supporting the upper roll of said pair and consisting of a block resting upon the gudgeon of the lower roll, a block bearing 25 against the gudgeon of the upper roll with one end of the upper block in contact with the corresponding end of the lower block and means for separating the opposite ends of said blocks, whereby the lower block is 30 crowded against the gudgeon of the lower roll and the upper block is crowded against the gudgeon of the upper roll, substantially as described.

2. The combination with a rolling-mill 35 housing and a pair of rolls held therein, of means for supporting the upper roll of said pair and consisting of a block resting upon the gudgeon of the lower roll, a block placed beneath the gudgeon of the upper roll with one 40 end of said upper block in contact with the corresponding end of the lower block, with the contacting ends of said blocks held in a free space within said housing whereby said contacting ends are capable of a vertical movement 45 as the rolls are adjusted vertically, and means for separating the opposite ends of said blocks, substantially as described.

3. The combination with the gudgeons of the upper and lower rolls of a rolling-mill, of a carrier for the top roll comprising a pair of 50 blocks placed one above the other and between the upper and lower roll gudgeons, each of said blocks having a beveled surface at one end, a wedge inserted between said beveled surfaces and means for actuating said wedge to support the beveled ends of said blocks while their opposite ends are held from vertical movement, thereby raising the upper of said blocks against the gudgeon of said upper roll, substantially as described. 55

4. The combination with a roll-housing and a pair of rolls held therein, of means for supporting the upper roll of said pair of rolls and consisting of a pair of blocks one above the other and inserted between the ends of the 60 upper and lower rolls, said blocks having opposing beveled surfaces at one end with their opposite ends held in contact, a wedge inserted between said beveled surfaces and provided with a screw-threaded hole and a bolt 65 journaled in said housing and held from longitudinal movement, said bolt having a screw-threaded end engaging said wedge to force it between said blocks, substantially as described. 70

5. The combination with a roll-housing and a pair of rolls held therein, of means for supporting the upper roll of said pairs of rolls and consisting of a pair of blocks inserted one above the other between gudgeons of the 80 upper and lower rolls, said blocks having short beveled surfaces at one end with their opposite ends in contact, a wedge inserted between the beveled surfaces of the blocks, and means for forcing said wedge between the 85 blocks. 75

In testimony whereof I have signed my name to this specification, in presence of two subscribing witnesses, this 1st day of June, 1900.

JEROME R. GEORGE.
